UNITED STATES PATENT OFFICE.

THOMAS DEAN, OF PATERSON, NEW JERSEY.

COMBINED WINDOW VENTILATOR AND SHADE.

SPECIFICATION forming part of Letters Patent No. 367,195, dated July 26, 1887.

Application filed April 20, 1887. Serial No. 235,480. (No model.)

To all whom it may concern:

Be it known that I, THOMAS DEAN, of Pater-
son, in the county of Passaic and State of New
Jersey, have invented a new and Improved
5 Combined Window Ventilator and Shade, of
which the following is a full, clear, and exact
description.

The object of my invention is to provide a
new and improved window ventilator and
10 shade, which permit of ventilating the room
without causing draft, and at the same time
serve as a window-shade.

The invention consists in the construction
and arrangement of various parts and details
15 and combinations of the same, as will be fully
described hereinafter, and then pointed out
in the claims.

Reference is to be had to the accompanying
drawings, forming a part of this specification,
20 in which similar letters of reference indicate
corresponding parts in all the figures.

Figure 1 is a front elevation, partly broken
away and in section, of my improvement. Fig.
2 is a side elevation of the same in a closed or
25 folded position. Fig. 3 is a similar view of the
same in an open position. Fig. 4 is a vertical
section of the same on the line *x-x* of Fig. 1,
showing the window open.

To the sides *A* of the window-casing and di-
30 rectly above the window-sill *B* are secured the
strips *C*, to the lower ends of which are hinged
the ends of an inverted-U-shaped frame, *D*,
extending upward and being of about the
same height as the window-casing. The side
35 arms of the frame *D* are each connected with
the strips *C* by the folding canvas strips *E*,
and the frame *D* can be held in a vertical
closed position, as shown in Figs. 1 and 2, by
40 the hooks *F*, pivoted to the sides of the win-
dow-casing and engaging with their hook ends
the pins *G*, secured to the sides of the U-shaped
frame *D*. The latter is held in an inclined
position, as shown in Figs. 3 and 4, by the arms
45 *H*, pivotally connected with each other at their
inner ends and pivoted at their outer ends to
the sides of the frame *D* and the sides *A* of
the window-casing, respectively.

On the upper end of the U-shaped frame *D*,
and in front of the same, is mounted in suitable
50 bearings on said frame *D* the spring shade-
roller *I*, of any approved construction, and car-

rying the shade *J*, provided near its lower end
with sidewise-extending guide-plates *K*, held
between and adapted to slide in guides *L* and
L', formed on the inner edges of each side of 55
the U-shaped frame *D*. The outer guide, *L*,
terminates a short distance below the shade-
roller *I* and bends outward to admit the guide-
plate *K*, as illustrated in Fig. 4. The shade-
roller *I* may be covered up by an ornamental 60
front plate, *N*, secured to the frame *D*, so as to
hide the roller and its bearings. Now, it will
be seen that the shade *J* can be pulled down
or let up fully or only partly in the closed or
opened position of the frame *D*, thus serving 65
as a shade in the usual manner for the windows
O, admitting or preventing the passage of the
rays of light, as desired.

When it is desirable to ventilate the room
without causing a draft, then the frame *D* is 70
placed in an inclined position, as shown in
Figs. 3 and 4, by unhooking the hooks *F* from
the pins *G* and then moving the frame *D* out-
ward from the window-casing until the folded
75 arms *H* are extended, as shown in Fig. 3. The
sashes of the windows *O* are then opened and
the shade *J* is pulled down so that the frame
D, the shade *J*, and the canvas strips *E* form
a casing in front of the window, which casing
is closed in front, at the bottom, and on the 80
sides, and is opened at the top, so that the fresh
air entering through the open sashes has to
pass upward in order to enter the room, thus
preventing draft.

The canvas strips *E* may be directly attached 85
to the sides *A* of the window-casing instead of
to the strips *C*, which may be entirely dis-
pensed with.

Having thus described my invention, what
I claim as new, and desire to secure by Let- 90
ters Patent, is—

1. In a window ventilator and shade, the
combination, with a U-shaped frame pivoted
to the lower ends of the window-casing, of a
window-shade secured to a roller hung on the 95
said U-shaped frame, substantially as de-
scribed.

2. In a window ventilator and shade, the
combination, with a U-shaped frame pivoted
to the lower end of the window-casing, of fold- 100
ing strips secured to the sides of the casing
and to the sides of the said frame, and a win-

dow-shade secured to a roller mounted on the said **U**-shaped frame, substantially as described.

3. In a window ventilator and shade, the combination, with a **U**-shaped frame pivoted to the lower end of the window-casing, of folding strips secured to the sides of the casing and to the sides of the said frame, means, substantially as described, for holding said frame to in an inclined opened position, and a window-shade secured to a roller mounted on the said **U**-shaped frame, substantially as described.

4. In a window ventilator and shade, the combination, with an inverted-**U**-shaped frame pivoted at its ends to the lower ends of the sides of the window-casing, of folding strips secured to the sides of the casing and to the sides of said frame, a shade-roller held on the upper end of said frame, and a shade mounted

on said roller and adapted to be moved on the **U**-shaped frame, substantially as shown and described.

5. In a window ventilator and shade, the combination, with an inverted-**U**-shaped frame pivoted at its ends to the lower ends of the sides of the window-casing, of folding strips connecting the sides of said frame with the sides of the window-casing, a shade-roller held on the upper end of said frame, a shade mounted on said roller, and guide-plates secured to the lower end of said shade and adapted to slide in guides formed on said **U**-shaped frame, substantially as shown and described.

THOMAS DEAN.
